POCKET FOR BILLIARD TABLES

Alfred F. Debicki, Muskegon, Mich., assignor to
The Brunswick-Balke-Collender Company,
Chicago, Ill., a corporation of Delaware

Application June 5, 1942, Serial No. 445,837

10 Claims. (CL 273—12)

This invention relates to billiard table pockets and particularly to the structure by which the pocket itself is supported in the table.

One object of the invention is to provide a new and improved supporting structure and ornamental covering therefor to carry and partly conceal a billiard table pocket.

Another object of the invention is to provide a relatively simple pocket-supporting member which can be easily made from sheet material and readily applied to the adjacent structure of the table.

A further object of the invention is to provide a support comprising unitary means for attachment to the table structure, positioning and supporting a buffer pad over the pocket, partially supporting the pocket itself and carrying an external ornamental shield to mask the supporting element and the pocket.

It is also an object of the invention to provide a pocket supporting member arranged to be secured adjustably to adjacent parts of the table structure to accommodate inaccuracies or irregularities therein, together with a shield ornamenteally masking the support and including means which overlap adjacent elements of the table structure.

Other objects and advantages will appear from the following description taken in connection with the drawing, in which:

Figure 1 is a fragmentary perspective view of one corner of a billiard table fitted with a pocket support and masking shield embodying this invention;

Figure 2 is a vertical sectional view on a larger scale, taken as indicated at line 2—2 of Figure 1;

Figure 3 is a detail section showing the pocket and its supporting structure in elevation and being taken on a smaller scale than Figure 2, as indicated at line 3—3 thereof;

Figure 4 is a plan section of the pocket and supporting structure, taken as indicated at line 4—4 on Figure 1;

Figure 5 is a detail section taken as indicated at line 5—5 on Figure 3.

While the invention is susceptible of various modifications and alternative constructions, the embodiment shown in the drawings and described hereinafter is by way of preferred illustration only, and it is not intended that the invention be limited thereto or thereby; but it is the intention to cover all modifications and alternative constructions falling within the

spirit and scope of the invention as defined by the appended claims.

The fragmentary illustration of a billiard table in Figure 1 includes the corner leg 1, with portions of the side frame 2 and end frame 3 engaged therewith, and with a portion of the bed or playing surface indicated at 4. Parts of the cushions 5, 5, are also shown extending from the cushion rails 6, 6, with their depending aprons 7, 7; and at the corner of the table the rails 6, 6, and the aprons 7, 7, extend to opposite sides of the corner pocket and the gap between them is bridged by the shield member 10 associated with the pocket structure and constituting a portion of this invention.

This ornamental shield member 10 may be understood as composed of relatively thin sheet metal, but if desired it might be constructed from some other sheet material such as vulcanized fibre or one of the various available plastic compositions. It is carried by a supporting member 11 of somewhat heavier sheet metal, and when both parts are made of similar metal, such as steel, they may be connected by spot welding, as indicated at 12 in Figure 4; otherwise the shield 10 may be attached permanently to the supporting member 11 by rivets or other suitable fastening means.

The member 11 includes a vertically extending web portion 13 with lateral flanges 14, 14, and laterally extending ears 15, 15, integral with the web 13. From the upper edge of the web 13 an arm 16 extends obliquely upward and inward, as seen in Figure 2. Each of the ears 15 is provided with a pair of horizontally extending slots 17 to receive fastening bolts 18 by which the pocket irons or support 11 are secured to rails 8, 8, attached to the edges of the bed 4 and built up with blocks 9, 9, to receive the ears 15, as shown in Figure 4. The bolts 18 are fitted with special tubular, flanged nuts 19 set into the rails 8 and blocks 9. The horizontally extending slots or openings 17 afford sufficient accommodation to permit the member 11 to be readily secured in place and to adapt itself to any slight irregularities or inaccuracies in the positions of the bolt holes in the rails 8, 8.

The pocket 20 itself is of the usual construction, being formed of leather with a circular bottom wall 21 and with a unitary side wall 22 which is slit at 23 and 24 to give the pocket an upwardly flaring shape. The material of the side wall 22 is lapped upon itself and secured by a suitable rivet 25 and the edge of the pocket di-

rectly above this fastening is attached to the table structure by tacks 26 serving as the suspension for one side of the pocket. At the opposite side the upper edge of the pocket has stitched to it a flexible tab 27 which extends upwardly against the under face of the overhanging oblique arm 16 of the support 11 and is attached thereto. The arm 16 also supports a buffer pad 30 having a resilient filling 31 and a flexible covering 32. Inside the pad 30 and under its resilient filling 31 there is positioned a metallic plate 33 perforated for engagement by a pair of fastening screws 34 which extend into threaded holes in the arm 16, as seen in Figure 5. The heads of the screws are accessible through holes 35 in the pad cover 32 and when the pad is thus secured to the arm 16, the flexible tab 27 is interposed between the pad and said arm, and is thus clamped between them, being also perforated to accommodate the screws 34.

The lateral flange portions 14, 14 of the support 11, serve to position the web portion 13 and the arm 16 outwardly from the parts of the table to which the ears 15 are secured so as to properly locate and center the pocket 20.

The shield member 10 includes lateral flanges 40 which closely embrace the flanges 14 and may be spot welded thereto, as shown in Figure 4. The flanges 14 and 40 are disposed adjacent the ends of the aprons 7, 7 of the table structure, and to neatly mask these ends, the shield includes wing portions 41, 41, which are shown as separate pieces, each with a flange 42 attached to the face of the adjacent flange 40 of the shield. If desired, these wing portions 41 might be made integral with the remainder of the shield; but it may be understood that the structure herein illustrated as applied to a corner pocket of a billiard table is adaptable for use at the side pocket when modified in only one or two particulars. For such location the ears 15, 15, of the pocket supporting member 11 will be bent at right angles to the flanges 14, 14, instead of at 135 degrees thereto as shown in Figure 4, and the wings 41 of the shield member will extend perpendicularly from the adjacent flange portions 40, lying flatly in a common plane for contact with two adjacent portions of the aprons 7 at the side of the table, instead of being curved back as shown in Figure 4 to engage the apron portions 7, 7, which are at right angles to each other. Accordingly the only difference between the shield for the corner pockets and the shield for the side pockets is in the formation of the wing portions 41 and it is therefore preferable to make the central portion of the shield as a separate member which can be employed both for the corner pockets and for the side pockets by merely adding to it the proper wings 41. As an ornamental feature the shield includes an angular step 43 at each side of its exposed face and the supporting member 11 is formed with a corresponding step or offset 44 interposed between the web portion 13 and each flange 14.

The upper end of the shield is curved inwardly at 45 with the extreme end portion 46 folded around the upper edge of the supporting arm 16 and conveniently clamped between the under face of said arm and the pad 30. At the lower edge the shield is bent inwardly in a bottom flange 47, which gives a finished appearance and avoids any sharp edges which might injure the player's hand when he lifts the flexible pocket 20 from below to remove a ball therefrom.

I claim:

1. In a pocket structure for billiard tables, a pocket support formed of sheet stock and comprising a vertically disposed web with lateral ears extending therefrom for attachment to the table structure and an arm extending obliquely upward and inward from the web portion, and means for suspending one side of a pocket from said arm.
2. In a pocket structure for billiard tables, a pocket support formed of sheet stock and comprising a vertically disposed web with lateral ears extending therefrom for attachment to the table structure and an arm extending obliquely upward and inward from the web portion, and means for suspending one side of a pocket from said arm, together with an ornamental shield secured to the outer face of said web extending upwardly over the oblique arm and extending downwardly by a distance substantially equal to the depth of the pocket.
3. In a pocket structure for billiard tables, a pocket support formed of sheet stock and comprising a vertically disposed web with lateral ears extending therefrom for attachment to the table structure and an arm extending obliquely upward and inward from the web portion, and means for suspending one side of a pocket from said arm, together with an ornamental shield secured to the outer face of said web extending upwardly over the oblique arm and extending downwardly by a distance substantially equal to the depth of the pocket, said shield having laterally extending wing portions to overlap the adjacent portions of the apron of the table.
4. In a pocket structure for billiard tables, a pocket support formed of sheet stock and comprising a vertically disposed web with lateral ears extending therefrom for attachment to the table structure and an arm extending obliquely upward and inward from the web portion, and a flexible tab secured to the under side of said arm and depending therefrom for attachment to a pocket.
5. In a pocket structure for billiard tables, a pocket support formed of sheet stock and comprising a vertically disposed web with lateral ears extending therefrom for attachment to the table structure and an arm extending obliquely upward and inward from the web portion, said arm having a threaded hole, and a pad disposed against the under side of the arm with a screw extending through the pad into said threaded hole in the arm.
6. In a pocket structure for billiard tables, a pocket support formed of sheet stock and comprising a vertically disposed web with lateral ears extending therefrom for attachment to the table structure and an arm extending obliquely upward and inward from the web portion, said arm having a threaded hole, and a pad disposed against the under side of the arm with a screw extending through the pad into said threaded hole in the arm, together with a flexible tab interposed between the pad and the arm and clamped between them, said tab depending therefrom for attachment to a pocket.
7. In a pocket structure for billiard tables, a pocket support formed of sheet stock and comprising a vertically disposed web with lateral ears extending therefrom, said ears having horizontal, elongated holes to engage fastening members in the table structure and said web having an arm extending obliquely upward and inward therefrom, and means for suspending one side of the pocket from said arm.
8. In a pocket structure for billiard tables, a

socket support formed of sheet stock and comprising a vertically disposed web with lateral ears extending therefrom for attachment to the table structure and an arm extending obliquely upward and inward from the web portion, and means for suspending one side of a pocket from said arm, together with an ornamental shield secured to the outer face of said web extending upwardly and inwardly from said oblique arm, with the end portion of the shield folded over the end of the arm, and a pad secured to the under side of the arm and overlapping said end portion of the shield.

9. In a pocket structure for billiard tables, a pocket support formed of sheet stock and comprising a vertically disposed web with lateral flanges extending inwardly therefrom toward the table structure and lateral ears extending from each of said flanges in position for securing

against the outer surface of said table structure, the web having also an arm extending inwardly from the web portion, and means for suspending one side of a pocket from said arm.

- 5 10. In a pocket structure for billiard tables, a pocket support comprising a vertically disposed web portion with lateral ears extending therefrom for attachment to the table structure and with an arm extending obliquely upward and inward from the web portion, a pad secured to the under side of said arm, a flexible tab depending from said arm for attachment to a pocket, and an ornamental shield covering the outer faces of said web and said arm and extending upwardly by a distance substantially equal to the depth of the pocket, said shield having laterally extending wing portions to overlap a portion of the apron of the table.

ALFRED F. DEBICKI.
